US00D798254S

(12) **United States Design Patent** (10) Patent No.: **US D798,254 S**
Kim et al. (45) Date of Patent: ** Sep. 26, 2017

(54) **STAND FOR TELEVISION RECEIVER**

(71) Applicant: **LG ELECTRONICS INC.**, Seoul (KR)

(72) Inventors: **Hyungwon Kim**, Seoul (KR); **Mikyung Kim**, Seoul (KR)

(73) Assignee: **LG ELECTRONICS INC.**, Seoul (KR)

(**) Term: **15 Years**

(21) Appl. No.: **35/501,320**

(22) Filed: **Feb. 5, 2016**

(80) **Hague Agreement Data**

Int. Filing Date: **Feb. 5, 2016**

Int. Reg. No.: **DM/089410**

Int. Reg. Date: **Feb. 5, 2016**

Int. Reg. Pub. Date: **Aug. 5, 2016**

(30) **Foreign Application Priority Data**

Aug. 5, 2015 (KR) 30-2015-0039632

(51) **LOC (10) Cl.** **14-03**

(52) **U.S. Cl.**

USPC **D14/126**

(58) **Field of Classification Search**

USPC D14/126

See application file for complete search history.
